Attorney.

UNITED STATES PATENT OFFICE.

VIRGIL A. HOLBROOK, OF LOS ANGELES, CALIFORNIA.

FIREPLACE.

Application filed May 25, 1921. Serial No. 472,586.

To all whom it may concern:

Be it known that I, VIRGIL A. HOLBROOK, a citizen of the United States, and a resident of Los Angeles, in the county of Los Angeles and State of California, have invented new and useful Improvements in Fireplaces, of which the following is a specification.

This invention relates to a fireplace structure, and has for its main object to improve the heating efficiency thereof. It will be understood in the consideration of the invention that fireplaces are usually constructed to embody a space surrounded and insulated by substantial walls of tile, brick or refractory material which are normally of solid or filled in construction. The back wall is continued upward and turns at an angle to provide the usual arch and to deflect heated air and products of combustion outwardly to induce radiation before this heated air and products of combustion find their way to the flue opening which is positioned immediately forward and above the arch. Obviously the amount of heated air radiated to the room is of relatively small proportion to that generated in the fireplace, inasmuch as large quantities of air are heated adjacent the heating element and are carried through the flue without radiating heat to the room. The usual fireplace structures, however, are credited with the advantageous feature of promoting efficient ventilation of the room or building in which they are used.

It is therefore an object of my invention to provide means whereby some of the heat of the gases coming in contact with the walls and the arch of the fireplace are caused to give up their heat and to convey same to the interior of the room or building in which the fireplace is located, so that the gases escaping through the flue carry away less heat and the efficiency of the fireplace is improved while retaining its advantageous features.

With these and other objects in view, which will appear hereinafter, I have illustrated and described a preferred embodiment of my invention in which I employ hollow tile of a well-known type comprising a plurality of thin walls surrounding a plurality of longitudinal passages or ducts. These tile are disposed so as to form a portion of the side wall of the fireplace, the entire back wall thereof and also the arch, as well as

a portion of the wall surrounding the flue opening adjacent the arch. Other tiles are positioned adjacent the floor, so that the passages therein extend longitudinally from a point exterior to the fireplace and communicate with the passages in the tiles forming the above mentioned walls. The tile forming the side walls are arranged with their passages substantially horizontal and communicating with the passages in the tile forming the back wall, which passages are disposed vertically. The tile forming the arch have their passages arranged in alignment with the aforesaid passages and these in turn communicate with another series of passages in other tiles partially surrounding the flue at the lower end thereof adjacent the arch. These latter tile communicate with tile imbedded in the upper part of the fireplace structure which tile are arranged with their passages extending longitudinally and terminating at the sides of the fireplace close to the adjacent wall of the room at a distance substantially above the floor and somewhat to the rear of the inlet opening. Thus, a large portion of the heat generated radiates readily through the thin walls of the tile and as a result a current of air is maintained through these passages coming from points adjacent the flue and being discharged at a point above the floor in the opening provided in the wall over the fireplace structure. This structure thus virtually surrounds the source of heat with currents of moving air which are isolated from actual contact or admixture with the products of combustion within the fireplace and after being thoroughly heated are discharged to the room.

It is apparent that in this manner the temperature of the products of combustion and heated atmospheric air passing to the flue are considerably reduced in temperature before escaping and the heat radiated through the thin walls of the tile is conserved and will not be wasted by escaping to the flue as ordinarily occurs in present fireplace structures. Incidentally this moving current of air aids in keeping the air within the room in constant circulation, the advantages of which are well known. It is found that by employing this structure in addition to the above mentioned benefits accruing therefrom, that the walls of the tile, and therefore the side walls and arch of the fireplace are cooled by these currents

of air and the refractory material of which they are constructed will not deteriorate as rapidly as in present structures, and will be prevented from attaining a temperature sufficient to sinter or fuse the refractory material of which they are made.

I have illustrated the two embodiments of my invention in the accompanying drawings, in which:

10 Fig. 1 is a view in plan section of a fireplace constructed in accordance with the invention, the air passages being provided by hollow tile used in the construction thereof.

15 Fig. 2 is a view in vertical section of the fireplace.

Fig. 3 is a view in side elevation thereof, showing the relative positions of an air inlet and an air outlet opening.

Reference being had particularly to Figs. 20 1 to 3 inclusive, I employ a plurality of hollow tile 6, 6, 8-8, 9-9, 10-10, and 11, 11, of refractory material such as fire clay. The tile are of the usual construction and are here shown as each formed with a plurality of longitudinal passages 12, open at each end and separated from adjacent passages by means of thin walls 13, and the outer passages are closed at their sides by walls 14, 14.

30 The tiles 6, 6 are disposed adjacent the floor 15 of the room in which the fireplace is installed and are each arranged with their passages extending longitudinally. One of the ends 16 of each of the tiles 6, 6 is disposed flush with the exterior side wall 18 of the structure within an opening 19 therein. The tile extends inwardly to terminate at the side wall 20 of the fire place which side wall is formed by the tiles 7, 7, which 35 are arranged with their passages extending horizontally and rearwardly to the back wall 21. The tile 6, 6 are joined to the tile 7, 7 by a mitre joint as at 22 so that the passages of the one tile communicate with corresponding passages in the other tile. The back wall is formed by the tile 8, 8, and 40 9, 9 which are arranged with their passages disposed vertically and communicating with corresponding passages in the tile forming 45 the side walls they being joined as at 23 by a mitre joint. The arch wall 24 of the fireplace is formed by the tile 10, 10 which 50 have their passages communicating with those in the back wall 21.

55 Positioned above the space 25 is the usual flue opening 26, partially surrounded by the walls 28 and 29. The wall 29 is formed by the tile 11, 11 arranged with their 60 passages extending vertically and in communication with corresponding passages in the arch wall. It is apparent now that the side walls, back wall, and the arch, all of which are subject to the greatest heat in a fireplace, are formed by the thin outer wall 65 of the tile and therefore the air within the

passages will be rapidly heated. The wall at the back of the flue opening will also be subject to that and the air in passing through the tile in this wall will become further heated.

70 In order to convey this heated air back to the room, there is provided at each side of the flue tile 12, 12 arranged with their passages extending horizontally from the tile 11, 11 to an opening 30 provided in each exterior side wall of the fireplace structure at a point substantially above and somewhat to the rear of the lower openings.

75 It will be observed that the arrangement of tile shown, which may be altered as occasion requires, permits of using standard sizes of tile of the simplest construction and form, and these tile serve the purpose of the refractory brick ordinarily used in such structures. The exterior of the structure which extends beyond a wall 31 of a room is formed with ordinary building brick 32 for the purpose of providing a rigid structure and insulating the heat, but the brick employed need not be refractory. Also the wall 80 of the structure need not be as thick as required in present types, inasmuch as the moving currents of air within the tile tend to prevent radiation of heat to these outer brick. For ornamental purposes only the 85 front wall 33 of the fireplace and the exterior side walls are finished with glazed tile 34. The inlet openings and the outlet openings are shown as provided with ornamental grilles 35.

90 The operation is as follows: Upon heat being generated within the fireplace by any of the usual means (not shown) heated air and products of combustion rise therefrom as indicated by the arrows and come in contact with all the surrounding walls. Upon the air and gases reaching the arch wall, they are deflected outwardly but upon passing across the opening at the base of the flue 95 are induced therein by the natural draft. The path taken by these gases is similar to that in present types of fireplaces and it is obvious that in such types of fireplaces a large percentage of the heat generated is carried away. Particularly after the walls 100 have attained a high temperature and do not absorb additional heat, it being understood that the heat carried from a fireplace to a room depends upon radiation and not upon air currents. In the case of the construction shown however heat passes rapidly 105 through the thin walls of the tile surrounding the zone of heat and the air therein is rapidly heated. The continuous passages from the lower opening to the upper opening 110 on each side of the fireplace permits of a continuous flow of air therethrough and the heat taken up by the air causes it to be set in motion. Thus, while heat is being 115 generated air enters the lower openings and 120

125 generated air enters the lower openings and 130

issues at greatly increased temperature from the upper openings. The temperature of the products of combustion and any air passing through the flow is greatly reduced and 5 less heat is lost thereby.

Upon heat being generated in proximity to the walls of the unit the air currents set up on the passages follow the path indicated by the arrows. The air absorbs and 10 conveys to the room a large percentage of the heat ordinarily lost to the flue. It will be observed that the air currents while absorbing all the heat passing through the wall of the unit preclude the possibility of the metal 15 walls taking on a temperature sufficient to injure the metal.

While I have shown and described specific embodiments of my invention and arrangements of the air passages, I do not limit 20 myself to the exact details of construction shown or to the specific arrangements of air passages set forth, but may alter the construction and arrangement within the meaning of the appended claims, without departing 25 from the spirit of my invention.

I claim—

1. A fireplace structure embodying a fireplace having the side and rear walls thereof formed of hollow tile, the side walls there- 30 of having horizontal passages, horizontal tile transversely extended from said side walls and having horizontal passages opening into a room and in communication with the passages in said side walls, the tile forming 35 said rear walls having vertical passages in communication with the horizontal passages of said side walls, a tile arch over said fireplace having inclined passages communicating with the vertical passages in said 40 rear wall, and other tile adjacent the flue and having vertical passages therein communicating with said inclined passages and having openings into the room substantially above said other opening, whereby currents 45 of air may be induced from points in the room near the floor through said horizontal, inclined and vertical passages for heating the air and discharging the same into the room.

50 2. A fireplace structure embodying a plurality of horizontally disposed tile arranged in vertical tiers and paralleling the front of the fireplace, with openings at the sides of the fireplace for receiving currents of air 55 from points near the floor, side walls formed of horizontally laid tile having passages communicating with said inlet passages, a plurality of vertical tile forming the rear wall and having passages therein communi- 60 cating with the passages in said side walls, an inclined arch formed of a plurality of tile having passages therein communicating with the passages in and extended substantially forward of said rear wall, a plural- 65 ity of vertically disposed tile having pas-

sages therein communicating with the inclined passages in the top, and horizontally disposed tile having passages therein communicating with said last mentioned vertical passages and open at the sides of the 70 fireplace at points substantially above said air inlets.

3. A fireplace structure embodying a plurality of horizontally disposed tile arranged in vertical tiers and paralleling the front of 75 the fireplace, with openings at the sides of the fireplace for receiving currents of air from points near the floor, side walls formed of horizontally laid tile having passages communicating with said inlet passages, a 80 plurality of vertical tile forming the rear wall and having passages therein communicating with the passages in said side walls, an inclined arch formed of a plurality of tile having passages therein communicating 85 with the passages in and extended substantially forward of said rear wall, a plurality of vertically disposed tile having passages therein communicating with the inclined 90 passages in the top, horizontally disposed tile having passages therein communicating with said last mentioned vertical passages and open at the sides of the fireplace at points substantially above said air inlets, and a flue formed in front of said last men- 95 tioned vertical tile for directing the products of combustion outwardly from the fireplace.

4. A fireplace structure having a fireplace and a flue at the top thereof for disposing of the products of combustion, a front wall 100 above the fireplace, and side and rear walls extending therearound, a lining for the fireplace having side walls composed of a plurality of horizontally laid hollow tile, and a rear wall composed of vertically laid hollow tile, a plurality of horizontally laid hollow tile extending laterally from the front portions of said side walls and open at the outer ends thereof providing air inlets, the 105 passages in said lateral tile being in communication with the passages in said side walls, and the vertical passages in said rear wall, an inclined arch formed of hollow tile and extending substantially forwardly from said rear wall and having passages therein 110 communicating with the vertical passages in said rear wall, and a back for said flue formed of hollow tile with vertical passages therein communicating with said inclined 115 passages and having outlets in the sides of 120 said fireplace, all of said tile being matched and fitted so as to provide circulation of air through said inlets from points near the floor and from said outlets at points substantially above the floor of the room.
